VANITY BENCH OR SIMILAR ARTICLE

Clytie Ann Thomson, Roanoke, Va.

Application April 21, 1950, Serial No. 9,412

Term of patent 14 years

(Cl. D15—11)

To all whom it may concern:

Be it known that I, Clytie Ann Thomson, a citizen of the United States and a resident of Roanoke, in the county of Roanoke and the State of Virginia, have invented a new, original, and ornamental Design for a Vanity Bench or Similar Article, of which the following is a specification, reference being had to the accompanying drawing, forming part thereof.

The single figure is a perspective view of a vanity bench or similar article showing my new design.

The undisclosed side is like the side shown.

I claim:

The ornamental design for a vanity bench or similar article, as shown and described.

CLYTIE ANN THOMSON.
